UNITED STATES PATENT OFFICE.

PAUL H. HAMILTON, OF CLEVELAND, OHIO, ASSIGNOR TO THE SANDS MANUFACTURING COMPANY, OF CLEVELAND, OHIO, A CORPORATION OF OHIO.

THERMOSTAT MECHANISM.

Application filed September 22, 1927. Serial No. 221,321.

The present invention relates to adjustable thermostatic control means for automatic fluid heaters, and has for its object the provision of an adjustable thermostatic structure in which the adjustable elements of the thermostat may be locked against accidental or unauthorized derangement or displacement.

It is a further object of the present invention to provide a thermostatic structure for automatic fluid heaters in which the adjusting means is locked against displacement and at the same time protected by means of a single removable unitary cap.

Further objects will appear from the following description of one form of embodiment of the device.

Referring to the drawings—

Figure 1 is a section of an automatic fluid heater provided with an embodiment of the invention;

Figure 2 is an enlarged detail view of the thermostat shown in Fig. 1 and with the locking cover in place;

Figure 3 is a similar view with the locking cover removed;

Figure 4 is an end view of the thermostat illustrated in the preceding figures and with the locking cover in place;

Figure 5 is a sectional view of the thermostat;

Figure 6 is a view of the locking cover; and

Figure 7 is a section thereof.

The automatic fluid heater shown in Fig. 1 comprises a casing or receptacle 1 provided with a gas burner 2 at the base thereof, a central flue 3 being provided to remove the products of combustion. The gas burner 2 is supplied with gas from a fuel supply pipe 4, the quantity of gas supplied to the burner being regulated in accordance with the temperature of the fluid in the receptacle 1 by means of a thermostat 5 mounted on the side of the boiler and having a portion 6 extending into the interior of the tank 1, and exposed directly to the heat of the fluid contained therein. The receptacle 1 may of course be lagged or insulated in the conventional manner if desired.

Referring more particularly to the thermostat, the same comprises a casing 7 having an inlet port 8 and outlet port 9, the passage between these ports being controlled by a disk valve 10 cooperating with a seat 11, as

shown in sectional Fig. 5. The valve 10 is normally urged against the seat by a spring 10^a. The casing 7 is provided with a boss 7^a for mounting the same on the receptacle 1.

The boss 7^a supports the tubular projection 6 which is of brass or similar metal having a relatively high coefficient of expansion, and has its outer end fixed in the boss 7^a and carries at its inner closed end a screw threaded portion or block 12. A rod 13 of invar or similar metal with a small coefficient of expansion is threaded at its inner end into the screw threaded member 12 and is provided with a sliding enlarged portion 14 at its outer end, which partially projects into a recess 7^b in the boss 7^a. A valve operating member 15 has one end resting against the end of the rod 13 in the recess 7^b, and its other end fixed or located within the valve member 10. It will therefore be seen that an increase in temperature of the fluid within the tank will cause the copper or brass tube 6 to expand at a greater rate than the invar rod 13 which will cause the valve 10 to move toward the seat 11 and thereby reduce the flow of gas. A cooling of the fluid in the tank or receptacle 1 adjacent the projection 6 will have the opposite effect, as it will cause a relative contraction between the tube 6 and the rod 13, thereby causing the gas valve 10 to open, increasing the flow of gas.

The temperature range in which the thermostat functions is rendered adjustable by rotating the rod 13 so as to vary the amount the rod 13 extends into the threaded end 12 of the brass tube 6. This is accomplished by rotating a collar 14 mounted on the outer or free end of the rod 13 within the recess 7^b which collar is pinned to the rod by means of a set screw. This collar carries an outwardly projecting member 16 which is angularly movable with respect to certain indicia 17, this movement altering the length of the invar rod with respect to the copper or brass tube 6 by virtue of the screw threaded member 12.

As the member 16 projects beyond the surface of the casing 7 the same is in a position to invite a tampering and unauthorized adjustment of the thermostat. It is also in a position to receive a chance blow which would be transmitted to the somewhat delicate assembly of thermostat elements. In order to prevent such unauthorized adjust-

- ment and possible damage and to lock the thermostat in any desired adjustment, a cap 18 of segmental form is provided. This cap which is of channel cross section as shown 5 in Fig. 7 carries on its inner edge a segmental rack 19 having a plurality of teeth or depressions formed to engage with the member 16 so as to hold the same in any one of a plurality of selected positions when the cap 10 is applied, the cap being held in position by means of an ear 20 constructed to receive a mounting screw 21. As shown, the rack 19 extends through an arc struck substantially from a center coincident to the axis of the 15 rod 13, whereby it properly engages and locks the member 16 in any position of adjustment thereof. A foot 22 at each end of the cap 18 cooperates with the ear 20 to hold the cap evenly and properly spaced from the 20 casing 7. This cap 18 also possesses the function of protecting the recess 7^b against the admission of foreign bodies which might interfere with the proper action of the thermostat mechanism.
- 25 It will also be evident that after the thermostat is adjusted to any selected position and the cap member 18 is applied, the element 16 will be held in an immovable position.
- 30 It will of course be understood that other modifications than that described may find embodiment within the scope of the appended claims.

I claim:

- 35 1. In a thermostat for fluid heaters, a recessed casing, means for adjusting said thermostat partially located within said recess, a removable segmental cap normally adapted to be placed over said recess, means for holding said cap in place and a plurality of feet 40 for spacing said cap from said casing.
2. In a thermostat mechanism, the combination with a casing having a recess, a valve in said casing and thermo-elements for 45 operating said valve, of a member in said recess and connected to one of said elements

and projecting outwardly therefrom for adjusting the operative relation of said thermostat elements to said valve, and a device 50 removably mounted on the walls of said casing and bridging said recess in the plane of movement of said member to guard the latter and provided on its inner wall with a series of elements which interlock with the outer end of said member to lock it in any 55 position of adjustment.

3. In a thermostat mechanism, the combination with a casing having a recess, a valve in said casing and thermo-elements for operating said valve, of a member in said recess 60 and connected to one of said elements and projecting outwardly therefrom for adjusting the operative relation of said elements to said valve, said member carrying a laterally extending arm, and a device removably mounted on the walls of said casing and bridging said recess in the plane of movement of said member to guard the latter and provided on its inner wall with a series of elements which interlock with the outer end 65 of said member to lock it in any position of adjustment, said device being cut away along one edge to expose the arm on said member.

4. In a thermostat mechanism, the combination of a casing having a recess, a valve 70 in said casing and inner and outer thermo-elements, said inner element being movable axially to operate said valve and movable rotatively to adjust its operative relation to said valve, of an operating member in said 75 recess and connected to said inner element and projecting outwardly therefrom, and a device removably mounted on the walls of said casing and bridging said recess in the plane of movement of said member and provided with means arranged to engage said member and lock it against movement about the axis of said inner thermo-element while permitting movement of the latter axially.

In testimony whereof, I have hereunto 80 subscribed my name.

PAUL H. HAMILTON.
